UNITED STATES PATENT OFFICE.

FRITZ JOHNSON, OF RACINE, WISCONSIN, ASSIGNOR TO THE CHAS. ALSHULER MFG. CO., OF RACINE, WISCONSIN, A CORPORATION OF WISCONSIN.

SEWING MACHINE.

Application filed May 5, 1923. Serial No. 636,858.

This invention relates more particularly to duplex or two-needle lock-stitch sewing machines having rotary hooks for carrying the needle threads around the bobbin threads.

Its main objects are to facilitate turning corners and to improve the appearance and quality of the work.

It consists in the construction, arrangement and combination of parts as hereinafter particularly described and pointed out in the claims.

In the accompanying drawing like characters designate the same parts in the several figures.

Figure 1 is a side elevation of a portion of a two-needle lock-stitch sewing machine embodying the invention, a portion of the bed plate being broken away to disclose mechanism below it; Fig. 2 is an enlarged plan view of the mechanism below the bed plate, the supporting bearings and connections of the mechanism being shown in horizontal section; Fig. 3 is an enlarged end view as seen from the left relative to Figs. 1 and 2, the bed plate being shown in section; Fig. 4 is a detail front view on a still larger scale, of the rotary hooks, bobbin cases, bobbins, needles, and parts associated therewith, the feed bar or dog, throat plate and bed or work plate being shown in section; and Figs. 5, 6 and 7 are diagrams illustrating the operation of the machine in turning a corner.

The machine comprises a vertically reciprocating needle bar 1, provided with needles 2, and connected with a horizontal actuating shaft (not shown) having bearings in an overhanging arm 3 of the machine frame and provided with a belt pulley 4. A shaft 6, supported by bearings 7, on and below a horizontal bed or work plate 8 parallel with the needle actuating shaft, is rotated synchronously with said shaft by a connection (not shown), and is provided with spiral gears 9 and with a feed eccentric 10.

A reciprocating feed bar 12, connected at one end with the eccentric 10, is provided with toothed dogs 13, which work in an opening in a throat plate 14 removably fitted in an opening in the bed plate 8, as shown in Fig. 4. The dogs 13 are formed with holes for the passage of the needles 2 in sewing.

Rotary hooks or shuttles 16 are mounted

on the upper ends of vertical shafts 17, which are provided with spiral gears 18, meshing with the gears 9. Relatively stationary bobbin cases 19, loosely mounted within the hooks or shuttles 16 coaxially therewith, are provided with lugs 20 for holding them against rotation with the hooks. Within the bobbin cases 19 are removably fitted bobbins 21, which are held in place therein by latches 22. The hooks 16 are rotated by the gears 9 and 18 at the rate of two revolutions to each reciprocation of the needles 2, and are adapted to take the thread from the needles and loop it around the bobbin threads, to form lock stitches therewith.

The mechanism thus far described is like or similar in construction and operation to that of well known duplex lock stitch sewing machines and need not be more specifically described.

The rotary hooks 16 with the bobbin cases 19 and bobbins 21, are carried by saddles or brackets 24 and 25, in which the shafts 17 of the hooks are journaled. At one end the saddles are formed with collars 26 and 27, which are mounted on sleeves or bushings 28 and 29, through which the shaft 6 passes, and which are fastened by set screws in the adjacent bearings 7, as shown in Fig. 2.

The collar 26 is split and clamped by a screw 30 on the sleeve 28, and the collar 27 pivots on the sleeve 29 and is held in place thereon by collars or flanges 31 and 32, the collar 32 being removably and adjustably fastened on the sleeve by a set screw.

At the end opposite the collar 26 the saddle 24 is adjustably fastened to the bed plate 8 by a screw 34 passing through a transverse slot in the saddle and threaded in the bed plate, as shown in Figs. 1 and 2.

At the end opposite the collar 27, the saddle 25 is forked and engages an eccentric 36 on a horizontal shaft 37, provided with an operating arm 38 and journaled at each side of the saddle in a forked bracket 39 adjustably fastened to the under side of the bed plate 8 by screws 40 passing transverse slots in the bracket and threaded in the bed plate.

A spring 41, connecting the arm 38 with the bed plate 8, tends to turn the arm upwardly and the eccentric 36 into position to hold the saddle 25 with its rotary hook 16 in position to co-operate with the adjacent needle 2. The arm 38 is connected by a rod 110

42 with a lever or other device (not shown) within convenient reach of the hand, foot or knee of the operator, for turning the arm and the saddle 25 down and lowering the 5 associated hook 16 with its bobbin case 19 and bobbin 21 into inoperative position, as shown in Fig. 4.

The lugs 20 on the right hand bobbin case 19, loosely engages a notch in or lugs 44 on 10 the throat plate 14, and the lug 20 on the left hand vertically movable bobbin case 19, loosely engages with a notch in or spaced lugs on the under side of an arm or stop 45, attached to and movable with the saddle 16 25, as shown in Fig. 4.

To provide a free passage between the leading side of the lug 20 and the lug with which it normally engages, for the withdrawal of the needle thread after it has been 20 looped around the bobbin and bobbin thread, a finger or drag arm 47 is adjustably fastened to a rocker arm 48, which is pivotally mounted on each saddle and is connected by a link or strap arm 49 with an eccentric 25 50 on the hook shaft 17. The eccentric 50 is set on the shaft 17 in position to turn the finger 47 inwardly into engagement with a projection 51 on the rim of the associated bobbin case 19 and to turn the bobbin case 30 slightly backward at the proper time to release the needle thread as it is withdrawn after being looped around the bobbin and bobbin thread.

The gears 9, and saddles 24 and 25, are 35 adjustable towards and from each other for varying the distance between the parallel seams as usual, and the bracket 39 which carries the eccentric 36 is adjustable on the bed plate 8 to allow for the adjustment of 40 the saddle 25.

In the operation of the machine, to turn a corner, as illustrated in Figs. 5, 6 and 7, two parallel seams *a b* and *c d*, are sewed along one side of the work, which is fed 45 in the direction indicated by an arrow on Fig. 5. When the inside or left hand needle 2 reaches the point *b*, the left hand hook 16 with its bobbin case and bobbin are dropped by the operator into inoperative position, as shown in Fig. 4, and the work 50 is fed in the same direction till the needles reach the points *d* and *e*, the left hand needle working idly without forming stitches from *b* to *e*, while the right hand needle continues the outside seam from the 55 point *f* to the point *d*. The machine is then stopped and the work is turned around the right hand needle or the point *d*, to the left, as indicated by an arrow, into the position shown in Fig. 6, in which the point *f* 60 is brought opposite the inside or left hand needle, whereupon the operation of the machine is resumed, the saddle 25 with the left hand hook being held out of operative position till the inside or left hand needle 65

reaches the point *b*. The saddle 25 is then released by the operator and the spring 41 returns it with the left hand hook 16, into operative position, the inside or left hand needle having worked idly, merely perforating the work from the point *f* to the point *b*, while the right hand needle with the associated hook 16 have functioned normally to produce stitches from *d* to *e*. The feed of the work being continued in the same direction, indicated by an arrow on Fig. 7, parallel seams *b g* and *e h* are sewed at the desired angle to the seams *a b* and *c d*. Two continuous parallel seams, *a b g* and *c d h*, are thus simultaneously made, turning corresponding corners at *b d* without stitching or carrying the thread across the space between them, the same as would be produced by separate operations with an ordinary one-needle machine.

Various modifications in the construction and arrangement of parts of the mechanism may be made without departing from the principle and scope of the invention as defined in the following claims.

I claim:—

1. In a sewing machine, stitch forming mechanism comprising two needles and rotary hooks one of which is movable out of and into operative relation to the associated needle, means operatively connected to the movable hook for yieldingly holding the same in operative position, and a manually operable member supported for movement in a given direction and operatively associated with said movable hook and said means for causing simultaneous yielding of the latter and movement of said hook to inoperative position upon movement in said direction, said yieldable means acting to return said hook to operative position upon release of said member.

2. In a sewing machine the combination with a reciprocating needle bar provided with two needles, of two rotary hooks adapted to cooperate with the needles to form stitches, hook supporting saddles one of which is movable with its hook out of operative position relative to the associated needle, bobbin cases centrally and loosely carried by the hooks, means holding the bobbin cases against rotation with the hooks, spring means acting on the movable saddle for yieldingly holding the same in operative position, and manually operable means engaging said saddle and arranged upon movement in a given direction to simultaneously effect yielding of said spring means and movement of said saddle to inoperative position.

3. In a sewing machine the combination with a vertically reciprocating needle bar provided with two needles, two horizontally rotatable hooks adapted to cooperate with the needles to form stitches and adjustable

horizontally towards and from each other to vary the distance between seams formed by the needles and hooks, one of said hooks being movable vertically at will into and out of operative position relative to the associated needle.

4. In a sewing machine the combination with a bed plate, a vertically reciprocating needle bar located above the bed plate, and provided with two needles, a horizontal shaft below the bed plate, and means for rotating said shaft, of saddles, one of which is movable vertically, located below the bed plate, hooks rotatably mounted on vertical axes in the saddles and geared with the horizontal shaft, and relatively stationary bobbins carried by the hooks coaxially therewith, one of the hooks and bobbins being shiftable at will with the vertically movable saddle into and out of operative position relative to the associated needle.

5. In a sewing machine the combination with stitch forming mechanism comprising reciprocating needles, rotary hooks, bobbin cases and bobbins for forming parallel seams with two threads, of a supporting member carrying one of the hooks with a bobbin case and bobbin into and out of operative position relative to the associated needle, a spring tending to retain said member with its hook, bobbin case and bobbin in operative position, and means for simultaneously overcoming the action of said spring and effecting movement of said member with its hook, bobbin case and bobbin out of operative position.

6. In a sewing machine the combination with a bed plate and stitch forming mechanism comprising a vertically reciprocating needle bar located above the bed plate and provided with needles and a rotary horizontal shaft located below the bed plate, of hook and bobbin supporting saddles supported at one end on said shaft, rotary hooks having vertical shafts journaled in the saddles and geared with said shaft, relatively stationary bobbin cases loosely and coaxially mounted within the hooks, an eccentric supported from the bed plate in engagement with one of the saddles, and means for turning the eccentric at will to shift the saddle with which it is connected and its hook out of operative relation to the associated needle.

7. In a sewing machine the combination with a bed plate and stitch forming mechanism comprising a vertically reciprocating needle bar located above the bed plate and a horizontal shaft located below the bed

plate, of saddles one of which is pivotally mounted to swing vertically on said shaft, rotary hooks having vertical shafts journaled in the saddles and geared with said shaft, bobbin cases loosely and coaxially mounted within the hooks and provided with lugs to hold them against rotation therewith, means for swinging the pivotally mounted saddle at will to shift its hook into and out of operative relation to the associated needle, and a stop on the pivotally mounted saddle engaging the lug on its bobbin case and holding it against rotation with the associated hook.

8. In a sewing machine the combination with a bed plate and stitch forming mechanism comprising a reciprocating needle bar located above the bed plate and provided with needles and a horizontal rotary shaft located below the bed plate, of saddles one of which is pivotally mounted to swing vertically on said shaft, rotary hooks having vertical shafts journaled in the saddles and geared with said shaft, bobbin cases loosely and coaxially mounted within the hooks, means for holding the bobbin cases against rotation with the hooks, a rocker shaft carried by the bed plate and provided with an operating arm and with an eccentric in engagement with the vertically movable saddle, and a spring connected with said arm and normally holding the movable saddle with its hook in operative relation to the associated needle.

9. In a sewing machine, the combination with a plurality of needles, and hooks supported and arranged for cooperation with said needles, one of said hooks being movable from operative to inoperative positions and vice versa, of yieldable means for holding said hook in one of said positions, and actuating means adapted and arranged to overcome the action of said yieldable means and to simultaneously move said hook to the other of said positions.

10. In a sewing machine, the combination with a pair of needles, hooks supported and arranged for cooperation with said needles, one of said hooks being movable from operative to inoperative positions and vice versa, of a spring for holding said hook in operative position, and manually operable means adapted and arranged to overcome the action of said spring and to simultaneously move said hook to inoperative position.

In witness whereof I hereto affix my signature.

FRITZ JOHNSON.
